[57] **ABSTRACT**

A bottle for storing and dispensing contents comprises at least one grip portion for improving a user's grip on the bottle. The grip portion is situated on the side of the bottle and extends at least partially along the height of the bottle and comprises a recessed grip panel formed in the side of the bottle adapted to receive the user's fingers and the grip panel is tapered at an angle with respect to the vertical direction. Preferably, the back of the bottle is thinner than the front so that a user can grip the bottle from the back. Preferably, there are a plurality of ribs inclined at a first angle with respect to the horizontal direction and a plurality of cross-hatch ribs inclined at a second angle, the second angle differing from the first at approximately ninety degrees and the ribs forming a lattice arrangement. Preferably, the bottle further comprises a plurality of ridges, situated on the side wall of the bottle for providing strength and rigidity to the bottle. The ridge is a depression across a part of the height of the bottle, has an underside, and extends at least partially along the side wall and comprises a lower portion that extends from the side wall toward the center axis of the bottle so that the contents beneath or on the underside of the ridge can be reached with a utensil.

BOTTLE WITH INTEGRATED GRIP PORTION

FIELD OF THE INVENTION

The present invention relates to bottles for storing and dispensing fluid, foodstuffs and other items, and more particularly to grip portions for such bottles.

BACKGROUND OF THE INVENTION

Bottles for storing and dispensing fluid and foodstuffs are well known. Most commonly, such bottles are blow-molded plastic containers that are hot-filled, i.e., filled when the product is in a hot state. Typically, such bottles are used to contain fluids, such as juices, or foodstuffs, such as sauces or jellies. Because such bottles are typically used repeatedly before their contents are consumed, they often have grip portions so that consumers can move the bottles to and from the refrigerator with a sure grip.

A typical prior art bottle having a grip portion is disclosed and described in U.S. Pat. Nos. D344,457; 5,392,937; and 5,598,941. The bottle shown in these patents has two grip portions, one on each side of the bottle. Each grip portion is a recessed portion to provide an area of reduced bottle width that is easier for a user to grip. The grip portions in these patents comprise ribs, oriented vertically, which are simply projections provided to further facilitate a better grip on the container. Other prior art bottles utilize horizontal ribs.

Prior art grip portions provide improved grips over conventional bottle designs. These grip portions, however, are basic improvements, and often do not provide a comfortable grip that is easy to use. It is, therefore, desirable to provide a grip portion for a bottle that is ergonomically designed and easier to use than conventional grip portions.

SUMMARY OF THE INVENTION

A bottle for storing and dispensing contents comprises at least one grip portion for improving a user's grip on the bottle. The grip portion is situated on the side of the bottle and extends at least partially along the height of the bottle and comprises a recessed grip panel formed in the side of the bottle adapted to receive the user's fingers and the grip panel is tapered at an angle with respect to the vertical direction.

In a preferred embodiment, the back of the bottle is thinner than the front so that a user can grip the bottle from the back. Preferably, the grip panel is adapted to receive user's fingers from the back of the bottle and further comprises at least one rib situated on the grip panel and inclined at an angle with respect to the horizontal direction. Preferably, there are a plurality of ribs inclined at a first angle and a plurality of crosshatch ribs inclined at a second angle, the second angle differing from the first at approximately ninety degrees and the ribs forming a lattice arrangement.

In another preferred embodiment of the present invention, the bottle further comprises at least one ridge, preferably a plurality, situated on the side wall of the bottle for providing strength and rigidity to the bottle. The ridge is a depression not more than 0.5 inch wide across a part of the height of the bottle, has an underside, and extends at least partially along the side wall and comprises a lower portion that extends from the side wall toward the center axis of the bottle so that the contents beneath or on the underside of a the ridge can be reached with a utensil. Preferably, a cross section of the lower portion of the ridge is a straight line extending from the side wall of the bottle at least partially toward the center

2

axis of the bottle and the ridge has an upper portion having a cross section of an arc extending from the side wall toward the center axis of the bottle so that the cross section of the lower portion of the ridge meets the cross section of the upper portion at a tangent.

Another aspect of the present invention includes a bottle having a plurality of ridges situated on the bottle's side wall for providing strength and rigidity to the bottle, wherein the ridges or depressions have varying widths across a part of the height of the bottle. In this embodiment, a first ridge having a width greater than the width of a second ridge provides greater strength and rigidity to the bottle at the first ridge's location than the second ridge provides at the second ridge's location.

BRIEF DESCRIPTION OF THE DRAWINGS

FIG. 1 is a side view of a bottle having a grip portion of the present invention.

FIG. 2 is a front view of the bottle of FIG. 1.

FIG. 3 is a longitudinal cross-sectional view of the bottle of FIG. 1 along line III—III.

FIG. 4 is a rear view of the bottle of FIG. 1.

FIG. 5 is a cross-sectional view of the bottle of FIG. 4 along line V—V.

FIG. 6 is a cross-sectional view of the bottle of FIG. 4 along line VI—VI.

FIG. 7 is an enlarged alternative view of section VII of the bottle of FIG. 1.

FIG. 8 is a side view of an alternative embodiment of a bottle having a grip portion of the present invention.

FIG. 9 is a rear view of the bottle of FIG. 7.

DETAILED DESCRIPTION OF THE PREFERRED EMBODIMENTS

The purpose of the present invention is to provide a grip portion for a bottle that is ergonomically designed and easier to use than conventional grip portions. FIG. 1 shows a side view of a bottle having a grip portion 20 according to the present invention. Preferably, there is one grip portion 20 on each side of a bottle. Each grip portion 20 comprises a grip panel 30, first and second triangular panels 22 and 24, and a trapezoidal panel 26.

Each preferred grip panel 30 comprises three inclined ribs 40, four finger slots 50, and eight cross-hatch ribs 42. The three inclined ribs 40 divide the panel 30 into four finger slots 50 for receiving a user's fingers. The two cross-hatch ribs 42 per each finger slot 50 are provided to prevent a user's fingers from sliding too far along the finger slot 50. Together, the inclined ribs 40 and the cross-hatch ribs 42 provide a lattice arrangement of ribs or ridges for ensuring a sure grip for a user. Preferably, as shown in FIG. 1, the angle γ between the inclined ribs 40 and the cross-hatch ribs 42 is between approximately 60 degrees, more preferably approximately 60 degrees, and most preferably approximately 90 degrees. FIG. 3 shows a longitudinal cross-sectional view of the bottle of FIG. 1 along line III—III.

FIG. 4 shows a rear view of the bottle of FIG. 1 and FIG. 2 shows a front view of the bottle of FIG. 1 (the back 60 and front 70 of the bottle are shown in FIG. 1). As shown in FIGS. 2 and 4, the inclined ribs 40 are inclined downward as they extend from the rear 60 of the bottle to the front 70. In addition, each grip panel 30 is tapered so that it is angled inward (toward the center of the bottle) as it extends from the bottom of the bottle to the top. FIG. 5 shows a cross-

sectional view of the bottle of FIG. 4 along line V—V. FIG. 6 shows a cross-sectional view of the bottle of FIG. 4 along line VI—VI.

As with prior art grip portions, a user places a hand over the back **60** of the bottle to grip the container with their thumb on one side and their four other fingers on the other side of the bottle. As shown in FIGS. 5 and 6, at the height of the grip portion **20** and grip panel **30**, the back **60** of the bottle is thinner than the front **70** so that the bottle is easier to grasp from the back **60**. When a user's hand is placed on the bottle, the thumb will naturally fit in the uppermost or second uppermost finger slot **50**. By means of the finger slots **50**, the grip panels **30** of the present invention provide places on a bottle for individually receiving the fingers of one's hand.

In addition, because the ribs **40** on the grip panels **30** are inclined, the finger slots **50** also are inclined, thereby providing easier gripping. It is believed that one naturally reaches for a bottle in a slightly downward direction because it is frequently below the height of one's elbow. Thus, as one reaches for a bottle having the grip portion **20** of the present invention, the user's fingers will naturally fall into place.

In the present invention, the amount by which the grip portions **20** are recessed varies from bottom to top. As shown in FIG. 4, the recessed area at the bottom of the grip portion **20** is not as great as the recessed area at the top of the grip portion **20**, which corresponds to the angle at which the grip panels **30** are tapered. As shown in FIG. 1, the first and second triangular panels **22** and **24** and the trapezoidal panel **26** connect the recessed grip panel **30** to the outer surface **80** of the bottle. The bottom side **90** of the grip panel **30** is attached directly to the outer surface **80** of the bottle.

The shape of the grip portions **20**, including the shoulder area **18**, also prevent the bottle from collapsing due to vacuum absorption. Bottles are often hot-filled, i.e., when the containers are filled with a fluid, the product is above room temperature. When the fluid is cooling down to room temperature, however, the bottle is affected by vacuum forces tending to cause the bottle to buckle or collapse inward. The bottle of the present invention prevents this collapse.

As shown in FIGS. 1, 2, and 4, the preferred bottle of the present invention also has horizontal ridges **82**, which are arc-shaped depressions that span the circumference or outer surface of the bottle **80** in between the grip portions **30**. These horizontal ridges **82**, as well as the lattice arrangement of the inclined ribs **40** and the cross-hatch ribs **42**, provide axial and radial strength and rigidity and help to prevent collapse due to vacuum absorption.

It is generally known that the thumb, index finger and middle finger perform most of the gripping, i.e., exert most of the gripping force, when one grips an object. Therefore, by means of the tapered grip panels **30**, the grip portion **20** of the present invention provides for the varying gripping force that a user's hand applies. The grip portion **20** is thinner where the user's hand exerts the most force and wider where the user's hand exerts the least force. In this way, a user's entire hand can be used to effectively grip the bottle.

The tapering of the grip panels **30** and the inclination of the inclined ribs **40** also contribute to the overall improved functionality of the bottle. When the contents are foodstuffs, such as peanut butter or apple sauce, the taper of the grip panels **30** allows for a user with a utensil, such as a butter knife or spoon, to scoop out the contents of the bottle. When inserted through the opening, a utensil such as a butter knife

will more naturally contact the side of the bottle at the grip panels **30**, thereby allowing a user to consume more of the contents and do so with greater ease. Similarly, the inclined ribs **40** allow a user to gain access to the area that the ribs **40** occupy.

Another aspect of the bottle of the present invention is depicted in FIG. 7. FIG. 7 shows an enlarged alternative view of section VII of the bottle of FIG. 1 around one of the horizontal ridges **82**. Prior art ridges, such as the horizontal ridges **82**, have semi-circular cross sections. The alternative improved ridge **821** of FIG. 7 enables a user with a utensil, such as a butter knife or spoon, to scoop out more of the contents of the bottle while the ridge **82'** still provides axial and radial strength and rigidity to help prevent collapse due to vacuum absorption. With semicircular ridges **82**, food-stuffs can hide beneath the underside of the ridge **82**, where a utensil cannot gain access because of the circular cross-sectional shape of the ridge **82**.

The cross section of a preferred improved ridge **82'** generally comprises an arc **83** forming the upper part of the ridge **821**, extending from the side **80** of the bottle to the center of the bottle, and a tangent line **84** forming the lower part of the ridge **82'**, extending from and tangential to the arc **83** to the side **80** of the bottle. Preferably, the width **W** of a ridge **82'** across a part of the height of the bottle is not more than approximately 0.5 inch. More preferably, the width **W** of a ridge **82'** across a part of the height of the bottle is approximately 0.3 inch for a 32 oz. bottle and is between approximately 0.23 inch and approximately 0.38 inch for a 64 oz. bottle.

Preferably, the tangent line **84** has an angle δ from the vertical side of the bottle **80** between approximately 5 degrees and approximately 45 degrees, more preferably between approximately 20 and approximately 45 degrees, and most preferably is approximately 40 degrees. In general, the benefit of the improved ridge **82'** will be realized if foodstuffs beneath or on the underside of a ridge **82'** can be reached with a utensil.

As shown in FIG. 7, width **WD** is the distance across a part of the height of the bottle measured from the point where the lower portion **84** of the ridge **82'** meets the side wall **80** of the bottle to the height up the side wall **80** to where the deepest point **85** of the depression of the ridge **82'** is located. Preferably, the width **WD** for each ridge **82'** is greater than or equal to half the value of the width **W** of the ridge **82'** across a part of the height of the bottle, i.e., $WD \geq \frac{1}{2}W$.

The amount of incline α , as shown in FIG. 1, of the inclined ribs **40** on the grip panels **30** may be varied to obtain optimum results. Preferably, the amount of incline is between approximately 5 degrees and approximately 25 degrees from horizontal (line **H** in FIG. 1), more preferably between approximately 10 degrees and approximately 20 degrees, and most preferably 15 degrees from horizontal. Alternatively, the ribs **40** may be constructed without any incline.

In addition, although it is preferred for the inclined ribs **40** to be inclined downward as they extend from the rear **60** of the bottle to the front **70**, the ribs **40** may be inclined upward within the principles of the invention. Users such as young children that reach upward for bottles would find such grip portions **30** to be advantageous. The foregoing angles specified for downward inclines also would be appropriate for upward inclines.

The angle β , as shown in FIG. 3, at which the grip panels **30** are tapered also may be varied to obtain optimum results.

Preferably, such angle is between approximately 2 degrees and approximately 25 degrees from vertical (line V in FIG. 3), more preferably between approximately 3 degrees and approximately 20 degrees, even more preferably between approximately 4 degrees and approximately 15 degrees, yet more preferably between approximately 5 degrees and approximately 10 degrees, and most preferably approximately 6 degrees from vertical.

An alternative embodiment of a bottle having a grip portion 20 according to the present invention is shown in FIG. 8. FIG. 9 is a rear view of the bottle of FIG. 8. The bottle of FIGS. 8 and 9 is larger than the bottle shown in FIG. 1, designed to accommodate a larger capacity. In preferred embodiments, the bottle of FIG. 1 is designed to hold approximately 32 ounces and the bottle of FIG. 8 is designed to hold approximately 64 ounces. A relatively large bottle, such as that in FIG. 8, is well suited for fluids such as juices, whereas a relatively small bottle, such as that of FIG. 1, is well suited for foodstuffs such as sauces or jellies.

For larger bottles, such as that of FIG. 8, more radial and axial strength is necessary to withstand greater vacuum absorption forces than those imposed on smaller bottles. Accordingly, with larger bottles, certain structural features are increased in size to accommodate for the increased forces. For example, with the bottle of FIG. 8, the horizontal ridges 82 may be larger than those of the bottle of FIG. 1 and/or also may vary in size on a particular bottle. As shown in FIGS. 8 and 9, key areas are reinforced, i.e., have larger horizontal ridges. These key areas where collapse is most undesirable, at heights near the top, middle and bottom of the grip panel 30, have horizontal ridges 82T, 82M and 82B, respectively, so that these areas have a lesser chance of collapsing due to vacuum absorption.

The bottle of the present can be made from conventional blow molding techniques used to manufacture plastic bottles. In addition, the bottle of the present invention may be manufactured using a spin trim blow molding technique in which one starts with a preform larger than is needed. Thus, a bottle is blow molded having an extra portion, typically a longitudinal extension, which is trimmed off to yield the finished bottle.

The present invention is further disclosed in commonly assigned U.S. Pat. No. Des. 420,587 entitled "Bottle with Integrated Grip Portion"; Ser. No. 29/096,813, Nov. 20, 1998, entitled "Bottle with Integrated Grip Portion"; and U.S. Pat. No. Des. 431,465, entitled "Bottle with Integrated Grip Portion", each of which is hereby incorporated by reference herein in its entirety.

It is to be understood that even though numerous characteristics and advantages of the present invention have been set forth in the foregoing description, together with details of the structure and function of the invention, the disclosure is illustrative only. Accordingly, changes may be made in detail, especially in matters of shape, size and arrangement of parts within the principles of the invention to the full extent indicated by the broad general meaning of the terms in which the appended claims are expressed.

What is claimed is:

1. A bottle for storing and dispensing contents, the bottle having a height and comprising:

at least a first side; and

at least one grip portion for improving a user's grip on the bottle, the first grip portion situated on the first side of the bottle and extending at least partially along the height of the bottle, the first grip portion comprising: a recessed grip panel formed in the first side of the bottle adapted to receive the user's fingers, said grip panel comprising:

a plurality of first ribs situated on said grip panel and inclined at an oblique angle with respect to a center longitudinal axis of the bottle, said first ribs forming a plurality of finger slots; and a plurality of second ribs situated on said grip panel, each inclined at an angle between approximately sixty and approximately ninety degrees to said first ribs to prevent the user's fingers from slipping in the finger slots.

2. A bottle for storing and dispensing contents, the bottle having a height and comprising:

at least a first side; and

at least one grip portion for improving a user's grip on the bottle, the first grip portion situated on the first side of the bottle and extending at least partially along the height of the bottle, the first grip portion comprising: a recessed grip panel formed in the first side of the bottle adapted to receive the user's fingers, said grip panel comprising:

at least two first ribs situated on said grip panel and inclined at a first oblique angle with respect to a center longitudinal axis of the bottle, said at least two first ribs forming a finger slot, and

at least one second rib situated on said grip panel at a second oblique angle with respect to the center longitudinal axis of the bottle to prevent the user's fingers from slipping in the finger slot.

3. The bottle of claim 2, wherein the difference between the first oblique angle and the second angle is approximately 60 degrees.

4. The bottle of claim 2, wherein the difference between the first oblique angle and the second oblique angle is approximately 75 degrees.

5. The bottle of claim 2, wherein the difference between the first oblique angle and the second oblique angle is approximately 90 degrees.

6. A bottle for storing and dispensing contents, the bottle having a height, a center axis, a side wall and at least one ridge situated on the side wall for providing strength and rigidity to the bottle, said ridge being a depression not more than 0.5 inch wide across a part of the height of the bottle, having an underside, and extending at least partially along the side wall and comprising a lower portion that extends from the side wall toward the center axis of the bottle so that the contents beneath or on the underside of said ridge can be reached with a utensil.

7. The bottle of claim 6, wherein a cross section of said lower portion of said ridge is a straight line extending from the side wall of the bottle at least partially toward the center axis of the bottle.

8. The bottle of claim 7, wherein the cross section of said lower portion of said ridge extends from the side wall at an angle between approximately 5 and approximately 45 degrees.

9. The bottle of claim 7, wherein the cross section of said lower portion of said ridge extends from the side wall at an angle between approximately 20 and approximately 45 degrees.

10. The bottle of claim 7, wherein the cross section of said lower portion of said ridge extends from the side wall at an angle of approximately 40 degrees.

11. The bottle of claim 7, wherein said ridge further comprises an upper portion having a cross section of an arc extending from the side wall toward the center axis of the bottle so that the cross section of said lower portion of said

ridge meets the cross section of said upper portion at a tangent.

12. The bottle of claim 6, wherein:

the lower portion meets the side wall at a first height on the bottle;

said ridge has a point of deepest depression that is closest to the center axis of the bottle and located at a second height on the bottle;

a second width across a part of the height of the bottle is the distance from the first height on the bottle to the second height on the bottle; and

the second width is greater than or equal to half the width of the ridge across a part of the height of the bottle.

13. A bottle for storing and dispensing contents, the bottle having a height, a side wall and a plurality of ridges situated on the side wall for providing strength and rigidity to the bottle, each ridge being a depression from the side wall, extending at least partially along the side wall and not more than 0.5 inch wide across a part of the height of the bottle, wherein at least a first ridge has a width greater than the width of a second ridge such that the first ridge provides greater strength and rigidity to the bottle at the first ridge's location than the second ridge provides at the second ridge's location.

UNITED STATES PATENT AND TRADEMARK OFFICE
CERTIFICATE OF CORRECTION

PATENT NO. : 6,164,474
DATED : December 26, 2000
INVENTOR(S) : Cheng et al.

It is certified that error appears in the above-identified patent and that said Letters Patent is hereby corrected as shown below:

Column 4, Line 11, delete "821" and insert --82'-- therefor.

Column 4, Line 21, delete "821" and insert --82'-- therefor.

Signed and Sealed this

Twenty-ninth Day of May, 2001
